(57) **ABSTRACT**

A shipping container made of two panels each made of recyclable, single face corrugated paper comprising an outer liner with corrugated medium. In one embodiment, the panels are formed from a large blank that is folded in half and joined at their side edges. The flutes on the corrugated mediums are parallel and longitudinally aligned with the shipping container's longitudinal axis. The top edge of each panel is detached and form a top opening into an interior pocket formed between the two panels. Formed or attach to one panel is a top flap configured to be folded over and selectively attached to the opposite panel to close the top opening. Formed on each corrugated medium is at least one set of score lines of various geometric shapes and orientations. The score lines act as folding lines that enable the panels to bend along different axes so that the overall shape of the shipping container better conforms to the object placed in the interior pocket. The sizes of flutes on each panel may be the same size or vary in size. The flutes on opposite panels may be axially aligned or offset. Improved

(Continued)

side edges attachment features are provided that reduce side edge separation and reduce thickness.

CONFORMABLE RECYCLABLE SHIPPING CONTAINER

TECHNICAL FIELD

This invention pertains to shipping containers, and more particularly to shipping containers made of material designed to partially conform to an object placed inside the shipping container.

BACKGROUND ART

Online retailers sell thousands of objects which are shipped to consumers. The objects come in different shapes and sizes and are usually distributed to consumers in outer packages.

Many online retailers use lightweight, inexpensive, flat envelopes called plastic bubble mailers to send products to customers. Most bubble mailers are made of multiple components, such as paper and plastic, can be recycled if the components are manually separated and delivered to a recycling facility that recycles the component. Unfortunately, most customers are unaware that the components must be separated and recycled so many bubble mailers used today still end up in landfills. Ideally, an alternative lightweight, inexpensive flat envelope made of corrugated paper that is 100% recyclable that can be directly placed in standard paper recyclable bin used by most homeowners and businesses is needed.

Mailers are manufactured in different sizes and shapes to accommodate different products. Because larger mailers are more expensive than smaller mailers, and take up more storage space than smaller mailers, and take up more shipping space than smaller packages, retailers try to use the smallest possible shipping container which can safely hold and protect the product. If a mailer is used that is larger than necessary to hold product, dead spaces may be created inside the mailer that allows the product to move inside the mailer during shipment. Sometimes, the retailer will add filler material to eliminate the dead spaces.

Sellers that ship large quantities of products to their customers must keep large quantities of empty shipping containers on hand. The size, shape and volume of the empty shipping containers determine the shipping container's shipping density. Generally, the more shipping containers that can be stored in a shipping box or bin, the less storage space for empty shipping containers is required by the seller.

What is needed is an improved flat, envelope-style shipping container made of non-recyclable material with two panels made of inner corrugated mediums that can be selectively manipulated to better conform the shipping container to different size and shape products. What is also needed is an improved shipping container that requires less storage space when in an empty configuration.

DISCLOSURE OF THE INVENTION

A conformable recyclable shipping container that includes at least two panels each with a paper outer liner and an interior paper corrugated medium. In one embodiment, the shipping container is made from a rectilinear or square blank designed to be folded in half to form stacked first and second panels. For discussion and illustration purposes, the flat shipping container is an envelope style container, called a mailer. It should be understood the shipping container may be different shapes and sizes and used for different purposes and not limited to the shipping industry.

2

In one embodiment, the blank is made of single face corrugate that includes a paper outer lining and paper corrugated medium. In the embodiments shown, the corrugated medium includes 'B' size flutes (approximately $\frac{1}{8}$ inch). It should be understood however the other size flutes (i.e. A-N) may be used.

Formed in the blank is a transverse, center crease line that divides the blank into a first panel and a second panel. When the blank is folded around the crease line, the first panel and second panel are aligned, registered, and stacked with their corrugated mediums facing inward. At least two of the side perimeter edges of the first and second panels are joined and form a large single interior pocket.

The flutes on the corrugated mediums are parallel and longitudinally aligned with the blank's longitudinal axis. The sizes of the flutes on each panel may be the same size or they may be different sizes. The spacing between flutes may be same or may also vary. The flutes on opposite panels may be axially aligned or offset. Also, different areas on each panel may have different size flutes or include crushed areas where the flutes have been flattened during manufacturing.

The top edge of each panel is detached forming a top opening into the interior pocket. Formed or attached to first panel is a top flap configured to be folded over and selectively attached to the outside surface of the opposite second panel to close the top opening. In one embodiment, a narrow flat section is formed adjacent to the top flap that forms a greater folding and contact area for the top flap when folded over the top edge of the second panel. Applied to the inside surface of the top flap is a suitable adhesive covered by a removable liner. The top flap may also include a tear strip that when pulled, tears the top flap, and separates it creating an opening to an internal pocket formed in the shipping container.

In another embodiment, the second panel may include a support flap that during assembly, folds over and attaches to the inside surface of the second panel to create a reinforced top edge.

Also, in another embodiment, the end section of each flute near the top opening may be crushed or flattened to form a beveled end surface enabling products to be more easily inserted into the interior pocket.

Formed on each panel and extending across the flutes are at least two score lines. The score lines act as supplemental folding lines in the main sections of the two panels that enable the shipper to independent bend each panel at different locations along the score lines to conform shipping container to the object placed in the interior pocket. In one embodiment, the score lines are parallel and diagonally aligned relative to the longitudinal axis of the flutes. The score lines may extend across the entire panel or part of the panel. The score lines on two panels may be aligned and registered or offset. Also, the width and depth of the score lines may be vary depending on the size and spacing of the flutes formed in the corrugated medium and the amount of bending desired.

The shipping container also includes improved side edges attachment features that securely join the adjacent side edges of the two panels. In one embodiment, the improved side edge attachment feature are two side edge extensions formed on each panel each with longitudinally aligned small flutes ('F' flutes). In another embodiment, two side edge extensions are formed on one panel and straight perimeter edges are formed on the opposite panel. The side edge extensions are configured to wrap around the straight perimeter edge and attached with an adhesive to the outside surface of the

opposite panel. When used with an adhesive, the small flutes increase the contact surfaces for the adhesive.

In another embodiment, each panel includes straight perimeter edges. A section on each panel adjacent to the perimeter edge may include small flutes ('F' flutes). When used with and adhesive the small flutes ('F' flutes) increases the contact area between the two joined surfaces that resist separation.

In both embodiments, because the small flutes nest, the overall thickness of the shipping container near its perimeter edges is reduced which increases shipping density.

BRIEF DESCRIPTION OF THE DRAWINGS

FIG. 1 is a top plan view of the shipping container disclosed herein with a beverage can placed inside the shipping container.

FIG. 2 is a right-side elevational view of the shipping container shown in FIG. 1.

FIG. 3 is a front side elevational view of the shipping container shown in FIG. 1.

FIG. 4 is a top plan view of the shipping container with the top opening opened showing an internal pocket and a beverage container placed inside the internal pocket.

FIG. 5 is a top plan view of one embodiment of a blank made of single face corrugate made up of an outer liner and a corrugated medium with a plurality of flutes and with diagonally aligned score lines formed on the corrugated medium, the blank being configured to be folded in half to form a first panel and a second panel each with at least one side edge extension.

FIG. 6 is a bottom plan view of the blank shown in FIG. 5.

FIG. 7 is a plan view of another embodiment of a blank made of single face corrugate also with a plurality of diagonally aligned score lines formed on the corrugated medium similar to the blank shown in FIGS. 5 and 6, each panel includes two straight side edges with a layer of adhesive on each side edge.

FIG. 8 is another embodiment of the blank like the blank shown in FIG. 5 with two zig-zag score lines formed on the corrugated medium on each panel.

FIG. 9 is another embodiment of the blank like the blank shown in FIG. 7 with two sets of diagonal aligned score lines formed on the corrugated medium on each panel, also shown two flute sizes on each panel.

FIG. 10 is a sectional view of the closed shipping container with the first and second panels folded over.

FIG. 11 is an illustration showing the scorings in a 45-degree diamond scoring line pattern.

FIG. 12 is an illustration showing the scoring lines in a 45-degree triangular scoring line pattern.

FIG. 13 is an illustration showing the scoring lines in a 60-degree diamond scoring line pattern.

FIG. 14 is an illustration showing the scoring lines in a 60-degree triangular scoring pattern.

FIGS. 15-17 show three different profiles of a scoring line in a flute.

FIG. 18 is a partial side elevational view of the shipping container showing an outer side wrap extension formed on one panel extending around the straight side edge on opposite panel, formed on the inside surfaces of the first and second panels are smaller flutes that nest to reduce to overall thickness of the shipping container along its perimeter edge, an adhesive is used to hold the outer side wrap extension on the first extension in place around the outsider surface of the opposite panel.

FIG. 19 is a partial side elevational view of the shipping container showing an outer side wrap extension formed on one panel with a flat surface being extended around the adjacent side edge on the opposite panel and attached with an adhesive.

FIG. 20 is a partial side elevational view of the shipping container showing two panel each with straight side edges, when the panels are folded together the stacked side edges are registered and aligned and attached with an adhesive.

FIG. 21 is a partial side elevational view of the shipping container showing two panels folded together with the two straight side edges with smaller flutes formed on their inside surfaces that are configured to nest and then attached with an adhesive.

FIG. 22 is a plan view of one embodiment of a blank made of single face corrugate similar to the blank shown in FIG. 5 but without the diagonal score lines and an optional support flap formed on the upper edge of the second panel.

FIG. 23 is a sectional view of the mailer made with the blank shown in FIG. 22 with the support flap wrapped around the second panel to reinforce the leading edge of the second panel.

BEST MODE FOR CARRYING OUT THE INVENTION

Referring to the Figs there is shown a conformable recyclable shipping container 10 that includes two panels 20, 40 each with an outer liner and a corrugated medium. In one embodiment, the shipping container 10 is made from a rectilinear or square blank 12 made of single face corrugated with a paper outer liner 15 and paper corrugated medium 16. The blank 12 is folded in half to form stacked first and second panels 20, 40. For discussion and illustration purposes, the flat shipping container 10 is an envelope-style container 10, often called a 'mailer'. It should be understood that the shipping container 10 may be different shapes and sizes and used for different purposes. In the embodiments shown, the corrugated medium 16 includes 'B' size flutes 18 (approximately $\frac{1}{8}$ inch wide). It should also be understood that the corrugated medium 16 is not limited to 'B' flutes and other flute sizes may be used (i.e. A-N).

The blank 12 includes a longitudinal axis 13 and transverse, mid-line axis 14. Formed in the blank 12 near the transverse mid-line axis 14 is a transverse crease line 19 that divides the blank 12 into two substantially equal size first panel 20 and second panel 40. When the blank 12 is folded around the crease line 19, the first panel 20 and second panel 40 are aligned, registered, and stacked with their corrugated mediums facing inward. The lower edges 30, 50 of the first panel 20 and the second panel 40, respectively, are integrally attached and the two side perimeter edges 32, 34 and 52, 54 of the first panel 20 and the second panel 40, respectively, are joined to form a large single interior pocket 70 as shown in FIGS. 1 and 4.

The flutes 18 on the corrugated mediums on each panel 20, 40 are parallel and longitudinally aligned with the blank's longitudinal axis 13. The sizes of the flutes 18 on each panel 20, 40 may be the same size or they may be different sizes. Also, the spacing between the flutes 18 may be uniform or they may vary. The flutes 18 on opposite panels 20, 40 may also be axially aligned or offset enabling the flutes on opposite panels to nest. Also, different areas on the corrugated medium used on each panel 20, 40 may have different size flutes 18 or include crushed areas 18a where the flutes 18 have either been flattened or not created during manufacturing.

The top edge of each panel **20, 40** is detached forming a top opening **60** into an interior pocket **70**. Formed or attached to first panel **20** is a top flap **62** configured to be folded over and selectively attached to the outside surface of the outer liner on the second panel **40** to close the top opening **60**. In one embodiment, the top flap **62** includes an extension section **63** that forms a larger folding and contact area for the top flap **62** when folded over the top edge **44** of the second panel **40**. Applied to the inside surface of the top flap **62** is a suitable adhesive **64** covered by a removable liner **65**. The top flap **62** may also include a tear strip **66** (see FIG. 6) that when pulled, tears the top flap **62** and separates it from the second panel **40**. When the top flap **62** is removed an opening is created into the internal pocket **70**.

As shown in FIGS. 4, 5, 7, 8 and 9, the end section **18B** of each flute **18** near the top flap **62** may also be crushed or flattened to form a beveled end surface enabling products to be more easily inserted into the interior pocket **70**.

FIG. 5 is a plan view of one embodiment of a blank **12** made of single face corrugated paper with wide side edge extensions **80** formed on each panel **20, 40** designed to form a wrap seal along the sides of the shipping container **10**. FIG. 5 also shows flutes **18** on panels **20** and **40** being longitudinally offset so the flutes **18** nest when the shipping container **10** is in a flat configuration.

FIG. 7 is a plan view of another embodiment of a blank, denoted **12A**, also made of single face corrugate also with a plurality of longitudinally aligned flutes **18**. The blank **12A** is configured to be folded in half to form a first panel and a second panel each with a layer of adhesive on each side edge. The side edges **32, 34** of the first panel and side edges **52, 54** of the second panel **40** are straight designed to be stacked together and attached with an adhesive **120** applied to the edges.

Formed on each panel **20, 40** and extending across the flutes **18** are at least two score lines **100-106**. The score lines **100-106** are non-perforating indentations formed in the flutes **18** and act as supplemental folding lines enable each panel **20, 40** to independently bend along different axes so the overall shape of the shipping container **10** better conforms to the object **100** placed in the interior pocket **70**. The score lines **100-106** may extend across the entire panel or a part of the panel. The score lines **100-106** on the two panels **20, 40** may be aligned and registered or offset. Also, the width and depth of the score lines **100-106** may be vary depending on the size and spacing of the flutes **18** formed in the corrugated medium and the amount of bending desired.

In FIG. 5, shows a plurality of diagonally aligned score lines **100** formed the corrugated medium on each panel **20, 40**. They score lines **100** are oriented from 5 degrees to 85 degrees from the longitudinal axis of the flutes **18**. FIG. 5 shows the score lines **100** on the panels **20, 40** in different directions. It should be understood that the number, the location, the position, and the spacing of the score lines **100** may vary on each panel **20, 40**.

In FIG. 7, shows another embodiment of the blank **12A** with a minimum of two sets of score lines (score lines **100, 102** shown) formed on the first panel **20** and no score lines are formed on the second panel **40**. In FIG. 7, the two sets of score lines **100, 102** are aligned in opposite directions at approximately 45 degrees from the longitudinal axes of the flutes **18**.

FIG. 8 is another embodiment of the blank **12B** similar to the blank **12** shown in FIG. 5 with side edge extensions **80** with two sets of zig-zag score lines **104** formed on the corrugated medium on each panel **20, 40**. The zig-zag score lines **104** on each panel **20, 40** are shown as being parallel

and extending transversely across each panel. It should be understood the number of zig-zag score lines **104** on a panel may vary, the orientation each zig-zag score **104** on the two panels, and they may also be diagonally aligned of each panel.

FIG. 9 is another embodiment of the blank **12C** similar to the blank **12A** shown in FIG. 7 with two sets of diagonal aligned score lines **100, 102** formed on the corrugated medium on each panel **20, 40**. FIG. 9 also shows the spacing and orientation of the two diagonally aligned score lines **100, 102** on the first panel **20** and the second panel **40** may vary.

Another optional feature of the invention is that the size of flutes **18** used in the first panel **20** and second panel **40** may vary. In one embodiment, the same size flutes **18** are used in both the first panel **20** and the second panel **40**. As stated above, the flutes **18** may be axially aligned or offset. FIGS. 5, 8 and 9 also show small flutes **18'** ('F' flutes) formed on the first panel **20** and second panel **40**. The small flute **18'** may be formed at different locations in the main body of each panel **20, 40** or they may be formed near the perimeter edges **32, 34, 52, 54** as discussed further below.

FIG. 10 is a sectional view of the shipping container **10** with the beverage container **200** shown in FIGS. 1-3 removed.

In addition to the simple patterns shown in FIGS. 5, 7 and 8, FIGS. 11-14 show four complex scoring line patterns **96, 97, 98, 99**, respectively, may be used on the first and second panels **20, 40**. As stated above, the angles of each score lines **100, 102, 104**, and **106** may vary. For example, FIG. 11 shows two score lines **100, 102** oriented to form a 45-degree diamond scoring line pattern **96**. FIG. 12 shows three score lines, **100, 102**, and **104** oriented to form a 45-degree triangular scoring line pattern **97**. FIG. 13 shows two score lines **100, 102** oriented to form a 60-degree diamond scoring line pattern **98**. FIG. 14 shows three score lines **100, 102**, and **106** oriented to form 60-degree triangular scoring pattern **99**.

The profile shape of each score line **100, 102, 104**, and **106** may also vary. For example, FIGS. 15-17 show end profiles of three non-perforated score lines (score line **100** shown only) formed in a flute **20** in the corrugated medium. It should be understood that the invention is not limited to these score line patterns or profiles.

The shipping container **10** also includes improved side edges attachment features that that securely join adjacent side edges of the panels and reduce the thickness of the shipping container **10** along the perimeter edges. In one embodiment, as shown in FIGS. 5, 6, and 8, the side edge attachment feature are two side edge extensions **80** formed on each panel **20, 40**. The side edge extensions **80** may be flat or may include longitudinally aligned small flutes **18'** ('F' flutes). In the embodiment, two side edge extensions **80** are formed on one panel **20** or **40** or one side edge extension **80** is formed on opposite sides of each panel **20, 40**. The side edge extension **80** is sufficiently wide to fold and wrap around the side edge on the adjacent panel. An adhesive **120** is used to attach the wrapped side edge extension to the outside surface of the opposite panel. In one embodiment, small flutes **18'** located area adjacent to the side edge extensions **80** are parallel to the flutes used on the main body. The small flutes **18'** may also be offset with the small flutes **18'** on the opposite panel so that flutes **18'** on the two panels **20, 40** may nest together.

FIGS. 7 and 9 show blank **12A, 12C** with straight side edges **32, 34, 52, 54**, that are aligned and registered when the

blanks are folded. When folded and stacked, the straight side edges 32, 34, 52, 54 are adhesively attached with a suitable adhesive 120.

Use of the side edge extensions 80 enable the entire widths of the corrugated mediums on each panel 20, 40 to be used. The side edge extensions 80 may be flat or they may include small flutes 18' ('F' flutes). Because the side edge extensions 80 are thinner than the main body of the panels, 20, 40, the overall thickness of the side edges of the shipping container 10 is reduced which is important for increasing shipping density.

FIG. 22 is a plan view of one embodiment of a blank indicated by reference number 12D made of single face corrugate like the blank shown in FIG. 5 but without the diagonal score lines. During assembly, the second panel 40 is folded over the first panel. Attached to the top edge of the second panel 40 and an optional support flap 160 that provides support for the top edge of the second panel 40 making it easier to insert or remove objects from the shipping container.

FIG. 23 is a sectional view of the blank 12D when assembled into a mailer showing the support flap 160 g wrapped around the top edge of the second panel 40 and attached to the inside surface of the second panel 40 with an adhesive 162.

This application claims priority to Patent Cooperation Treaty application no. PCT/US2020/061877, filed Nov. 23, 2020, which entered the U.S. national stage as U.S. patent application Ser. No. 17/778,339, filed May 19, 2022, the full disclosure of which application(s) is hereby incorporated herein by reference in its entirety.

In compliance with the statute, the invention described has been described in language more or less specific as to structural features. It should be understood however, that the invention is not limited to the specific features shown, since the means and construction shown, comprises the preferred embodiments for putting the invention into effect. The invention is therefore claimed in its forms or modifications within the legitimate and valid scope of the amended claims, appropriately interpreted under the doctrine of equivalents.

INDUSTRIAL APPLICABILITY

This invention has utility in industries that used corrugated containers, such as in the shipping and mailing industries.

We claim:

1. A recyclable shipping container, comprising:
a single face corrugated material that includes an outer liner layer and an inner corrugated layer, the inner corrugated layer including a plurality of flutes;
wherein the single face corrugated material is folded along a fold line that divides the corrugated material between a first panel and a second panel opposite to the first panel across the fold line;
wherein the first panel includes a first side edge portion that extends parallel to the flutes and a second side edge portion that extends parallel to the flutes;
wherein the second panel includes a first side edge portion that extends parallel to the flutes and a second side edge portion that extends parallel to the flutes, and the second panel includes an external surface;
wherein the first panel includes a main body and a first side wrap extension coupled to the main body at the first side edge portion of the first panel, the first side wrap extension includes a first free end edge at which the first side wrap extension terminates;

wherein the flutes extend across the main body of the first panel and do not extend across the first side wrap extension of the first panel from the first side edge portion to the first free end edge; and

wherein the first side wrap extension of the first panel extends around the first side edge portion of the second panel to couple the first free end edge of the first side wrap extension of the first panel to the external surface of the second panel in close proximity to the first side edge portion of the second panel.

2. The recyclable shipping container of claim 1 wherein the first side wrap extension of the first panel is coupled to the external surface of the second panel in close proximity to the first side edge portion of the second panel by an adhesive.

3. The recyclable shipping container of claim 1 wherein the first panel includes a second side wrap extension coupled to the main body at the second side edge portion of the first panel, the second side wrap extension includes a second free end edge at which the second side wrap extension terminates;

wherein the flutes do not extend across the second side wrap extension of the first panel from the second side edge portion of the first panel to the second free end edge of the second side wrap extension;

wherein the second side wrap extension of the first panel extends around the second side edge portion of the second panel, to couple the second free end edge of the second side wrap extension of the first panel to the external surface of the second panel in close proximity to the second side edge portion of the second panel.

4. The recyclable shipping container of claim 3 wherein the second side wrap extension of the first panel is coupled to the external surface of the second panel by an adhesive.

5. The recyclable shipping container of claim 1 wherein the second panel includes a main body a second side wrap extension coupled to the main body at the second side edge portion of the second panel, the second side wrap extension includes a second free end edge at which the second side wrap extension terminates;

wherein the flutes extend across the main body of the second panel and do not extend across the second side wrap extension of the second panel from the second side edge portion to the second free end edge;

wherein the second side wrap extension of the second panel extends around the second side edge portion of the first panel, to couple the second side edge portion of the second panel to the second side edge portion of the first panel.

6. The recyclable shipping container of claim 5 wherein the second side wrap extension of the second panel is coupled to the first panel by an adhesive.

7. A recyclable shipping container, comprising:
a single face corrugated material that includes an outer liner layer and an inner corrugated layer, the inner corrugated layer including a plurality of flutes;
wherein the single face corrugated material is folded along a fold line that divides the corrugated material between a first panel and a second panel opposite to the first panel across the fold line;

wherein the first panel includes a first side edge portion that extends parallel to the flutes and a second side edge portion that extends parallel to the flutes;

wherein the second panel includes a first side edge portion that extends parallel to the flutes and a second side edge portion that extends parallel to the flutes;

wherein the first panel includes a main body and a first side extension coupled to the main body at the first side edge portion of the first panel;

wherein the flutes extend across the main body of the first panel and do not extend across the first side extension of the first panel;

wherein the first side extension of the first panel is coupled to the first side edge portion of the second panel, and the flutes are not present at a region of the second panel at which the first side extension is coupled to the second panel.

8. The recyclable shipping container of claim 7 wherein the first side extension of the first panel is coupled to the first side edge portion of the second panel by an adhesive.

9. The recyclable shipping container of claim 7 wherein the first panel includes a second side extension coupled to the main body at the second side edge portion of the first panel;

wherein the flutes do not extend across the second side extension of the first panel;

wherein the second side extension of the first panel is coupled to the second side edge portion of the second panel.

10. The recyclable shipping container of claim 8 wherein the second side extension of the first panel is coupled to the second side edge portion of the second panel by an adhesive.

11. The recyclable shipping container of claim 7 wherein the second panel includes a main body and a first side extension coupled to the main body at the second side edge portion of the second panel;

wherein the flutes extend across the main body of the second panel and do not extend across the first side extension of the second panel;

wherein the first side extension of the second panel is coupled to the second side edge portion of the first panel.

12. The recyclable shipping container of claim 11 wherein the first side extension of the second panel is coupled to the first panel by an adhesive.
